UNITED STATES PATENT OFFICE.

HARRY M. McCALL, OF PITTSBURG, PENNSYLVANIA.

SPEED-REGULATOR FOR EXPLOSIVE-ENGINES.

SPECIFICATION forming part of Letters Patent No. 761,599, dated May 31, 1904.

Application filed July 14, 1903. Serial No. 165,434. (No model.)

To all whom it may concern:

Be it known that I, HARRY M. McCALL, a citizen of the United States, residing at Pittsburg, in the county of Allegheny and State of Pennsylvania, have invented certain new and useful Improvements in Speed-Regulators for Explosive-Engines, of which the following is a specification, reference being had therein to the accompanying drawings.

10 This invention has relation to speed-regulators for explosive-engines; and it consists in the novel construction and arrangement of its parts, as hereinafter shown and described.

15 The object of the invention is to provide a mechanism used on large types of hydrocarbon-engines, the mechanism being so located that it is easy of access and being so constructed that a nicety of adjustment may be attained to insure the proper mixture of air 20 and gas used in the charge.

25 The type of valve to which the mechanism is applicable consists of a casing having a valve adapted to move longitudinally therein to regulate the proportions of air and gas constituting the mixture and to rotate within said casing to regulate the quantity of the mixture fed to the engine without changing the proportions of air and gas constituting the mixture. The means for moving the valve 30 longitudinally may be operated by hand and at will either while the engine is at rest or in motion, while the means for rotating the valve is operated by the governor movement of the engine, and consequently takes place automatically, and the quantity of the charge is regulated according to conditions and the load under which the engine is laboring.

35 In the accompanying drawings, Figure 1 is a side elevation of the device. Fig. 2 is a 40 vertical sectional view of the type of valve to which the device is applicable. Fig. 3 is a vertical sectional view of the governor mechanism. Fig. 4 is a detailed side elevation of the collar adapted to connect the governor mechanism with the valve-operating mechanism. Fig. 5 is a face view of the disk used 45 on the valve-stem. Fig. 6 is a top plan view of the support for said disk, and Fig. 7 is a top plan view of the connection between the

valve-stem and the valve-operating mech- 50anism.

The valve consists of the casing 1, having an air-inlet port 2 and a gas-inlet port 3, with a mixture-outlet port 4 located between the two. The lining for said casing 1 consists of 55 a bushing 5, having at its upper end a series of ports 6, located opposite the chamber 7, which registers with the air-inlet port 2, said bushing having at its lower end a series of openings 8, located opposite the encircling 60 chamber 9, which registers with the gas-inlet port 3. The valve proper is located within the bushing 5 and consists of the members 10 10, having space between their inner ends and being attached to the stem 11, common to 65 both. Each of the said members 10 10 is provided with openings 12 12, which coöperate with the openings 6 and 8 of the air-inlet ports and gas-inlet ports, respectively.

In the operation of the valve a longitudinal 70 movement of the stem with relation to the bushing 5 varies the proportions of the air with relation to the gas, while a partial rotation of the valve cuts off both the air and the gas, but does not change their relative proportions. In order to effect the movement of the valve proper above described in a suitable manner, the present invention is provided. The stem 11 of the valve extends through the lower head of the valve-casing 1 and is provided with a thread 13. A portion of the said valve-stem 11 is flattened, as at 14, and is provided with a graduating-scale 15. The internally-screw-threaded disk 16 is adapted to engage the thread 13 of the said stem 11 and 80 passes vertically over the said scale 15. The disk 16 is provided in its periphery with an annular groove 17, which receives the lower bifurcated end of the support 18, the upper end of which is secured to the casing 1. The 85 said support 18 retains the disk 16 in a fixed horizontal position with relation to the casing 1, but permits the said disk to be rotated in a horizontal plane. As the said disk is rotated the thread thereof engaging the thread 90 of the stem 11 moves the said valve longitudinally in the bushing 5, the arrangement of the scale 15 being such as to indicate the 95

movement of the valve with relation to the bushing 5 as the units of the scale come into horizontal register with either the upper or lower surface of the said disk 16. The said 5 disk may be rotated while the engine is at rest or in operation, and the ease of access to the connection between the said disk and the valve-stem is of such a nature that a very delicate adjustment of the valve may be attained 10 at any time in order to effect the proper proportions of the elements constituting the mixture. For rotating the valve with relation to the bushing 5 a mechanism is provided which operatively connects the valve-stem 11 15 with the governor mechanism, which in turn is operated by the crank-shaft of the engine, (not shown in the drawings,) said governor mechanism consisting of a rotating shaft 19, carrying a yoke 20, to which the governor- 20 weight arms 21 are fulcrumed. Said arms carry at their lower end the weights 22 and have their upper ends slotted, as at 23, said slots receiving the pins 24, attached to the ring 25, which in turn is journaled to the sleeve 26, 25 which receives in its central opening the upper end of the shaft 19. The lower end of the collar 27 is received between the annular flanges 28, located at the upper end of the sleeve 26. The upper portion of the collar 27 is 30 pivotally connected to one end of the bell-crank lever 29, said bell-crank lever being fulcrumed at a point 30 to any convenient part of the engine. One end of the rod 31 is pivoted to the other end of the bell-crank lever 29, and 35 the opposite end of the said rod 31 is pivoted to the arm 32, which extends radially from the lower end of the valve-stem 11. The said arm 31 passes through a guide 33, attached to any convenient part of the engine, and is 40 provided with an adjustable nut 34, between which and the said guide 33 is interposed a coil tension-spring 35. The tension of said spring 35 is sufficient to maintain the governor-weights 22 in the nearest possible 45 positions toward each other, and consequently the tension of the said spring must be overcome by the centrifugal force operating upon the governor-weights 22 before the rod 31 can be moved longitudinally. 50 The operation of the mechanism just above described is as follows: The shaft 19 being in rotation, the governor-weights 22 are revolved, the centrifugal force spreading the said weights apart, which causes the upper 55 ends of the arms 21 to descend, which, through

the pins 24 and ring 25 engaging the said arms, causes the sleeve 26 to descend along the shaft 19, the said sleeve carrying down with it the collar 27, which draws down the lower end of the bell-crank lever 29, causing 60 the other end of the said lever to describe an arc away from the valve-casing 1 and causes the rod 31 to move longitudinally, overcoming the tension of the spring 35, as above described, and drawing around the arm 32 and 65 partially rotating the valve-stem 11, and thereby moving the openings 12 in the valve members to one side with relation to the openings 6 and 8 in the bushing 5 and reducing the quantity of the elements constituting the mix- 70 ture without altering their proportions.

The above operation takes place as the speed of the engine accelerates, and as the speed diminishes the operation above described is reversed, caused by the extra ten- 75 sion placed on the spring 35, which moves the rod 31 and its connection to their normal positions.

By adjusting the nut 34 on the rod 31 the tension of the spring 35 may be regulated to 80 require a greater or less amount of centrifugal force to operate the governor-weights, and by so doing the speed of the engine may be regulated to meet the conditions of the work to be performed. 85

Having described my invention, what I claim as new, and desire to secure by Letters Patent, is—

A mechanism for operating a valve consisting of a casing having a projecting valve-stem, 90 a means for moving said valve longitudinally at will consisting of a rotatable disk having a threaded perforation receiving said valve-stem, and a means for holding said disk in a fixed horizontal position with relation to the 95 valve-casing, a rod connected to the stem and adapted to rotate the same, a governor mechanism connected with and adapted to operate said rod, a spring engaging said rod, the tension of which is opposed to the movement of 100 the governor, said disk being adapted to be operated while the governor is in operation and without disconnecting said rod.

In testimony whereof I affix my signature in the presence of two witnesses.

HARRY M. McCALL.
